(57) **CLAIM**

I claim the ornamental design for a protective head gear, as shown and described.

DESCRIPTION

FIG. 1 is a front view of a protective head gear showing my new design;

FIG. 2 is a left side view thereof;

FIG. 3 is a right side view thereof;

FIG. 4 is a rear view thereof; and,

FIG. 5 is a top view thereof.

The details shown in broken lines form no part of the claimed design.
